UNITED STATES PATENT OFFICE.

HENRY LEVERENTZ, OF CHICAGO, ILLINOIS.

PLANING-MACHINE ATTACHMENT.

SPECIFICATION forming part of Letters Patent No. 316,156, dated April 21, 1885.

Application filed December 2, 1884. (No model.)

To all whom it may concern:

Be it known that I, HENRY LEVERENTZ, a citizen of the United States of America, residing at Chicago, in the county of Cook and 5 State of Illinois, have invented certain new and useful Improvements in Planing Machine Attachments, of which the following is a specification, reference being had therein to the accompanying drawings.

10 My invention relates to an improved planing-machine attachment.

The object of my invention is to provide an attachment for such machines by the use of which the sharpening of the cutter-heads there- 15 of is facilitated; and to the accomplishment of that end the invention consists of the novel devices and combination of devices as will be described.

Reference will be made to the accompanying drawings, in which Figure 1 is a plan view of the attachment, showing part of the machine-frame; and Fig. 2, a longitudinal section thereof.

Like letters refer to like parts in each view. 25 A A' represent parts of the machine-frame, and B the cutter-head thereof, each of any well-known construction. In that part of the frame marked A a shaft, C, has bearing, said shaft being driven by any suitable mech- 30 anism—such as belting and pulleys. Upon shaft C there is also mounted a pulley, D, around which belting D' is passed, this belting being also passed around a pulley, E, mounted upon one end of an arbor, F, through the medium 35 of which connections motion is imparted to said arbor.

Arbor F has bearings in a frame, G, consisting of suitable side and cross pieces, as shown clearly in Fig. 1, and which is loosely 40 mounted at its rear end upon shaft C, hereinbefore referred to.

Mounted upon a feather (not shown) formed on arbor F is an emery-wheel, H, which by this arrangement is made laterally adjustable. 45 The hub of wheel H is grooved suitably to receive a handle, J, through the medium of which the lateral adjustment of such wheel H upon arbor F is accomplished.

Formed upon the side rails of frame G are 50 brackets a, each provided with a screw-thread-

ed opening, through which a thumb-screw, K, is passed. As hereinbefore mentioned, frame G is loosely mounted at its rear end upon shaft C, and is therefore rendered adjustable, as indicated in dotted lines, Fig. 2.

The arrangement of the several parts is such that when lowered the front end of frame G will occupy a position above the cutter-head shaft, thereby enabling the emery-wheel to be brought into contact with the cutter-head.

The thumb-screws K referred to are adapted to contact with parts b of the frame of the machine, whereby the exact position of the emery-wheel with respect to the cutter-head can be determined.

During the process of sharpening, a block, L, (dotted lines, Fig. 2,) is placed beneath the blade being operated upon, to steady it and insure uniformity in the edge, said block having suitable support at its lower end upon 70 the machine-frame.

The operation of the device is as follows: When the cutter-heads are in use and it is not desired to sharpen the cutters thereof, the frame G is raised through the medium of any 75 suitable handle, as M, to the position shown in dotted lines in Fig. 2, where it is convenient to reach it, but not in the way of the successful working of the machine. When it is desired to sharpen the cutters, the thumb-screws are adjusted to determine the position 80 of the frame, and said frame lowered until such screws reach their supports. Motion is then imparted to shaft C, and through the medium of the belt-connections described to the 85 arbor F and emery-wheel H. The block M being then placed under the cutter to be operated upon, the operator moves the emery-wheel laterally upon arbor F and over the cutter, thereby sharpening the entire cutter uniformly 90 throughout. When all the cutters have been sharpened, the frame is again carried to its first position, the block removed from beneath the cutter, and the planing-machine is again ready for use.

I am aware that a swinging frame has heretofore been mounted upon a planing-machine frame, said frame being horizontally adjustable, and the sharpening device being stationary on its shaft as far as its horizontal adjust- 95 100

ment is concerned, and also that a planing-machine has been constructed with a stationary frame in which has been mounted a horizontally-adjustable sharpening device, and 5 therefore I lay no claim to either of such features separately; but

What I claim is—

In a planing-machine, the combination, with the frame thereof, of swinging frame G, loosely 10 mounted upon shaft C, shaft F, mounted in

frame G, sharpener H, adjustably mounted on shaft F, and adjusting and supporting screws K, all arranged as and for the purpose set forth.

In testimony whereof I affix my signature in presence of two witnesses.

HENRY LEVERENTZ.
